PANEL MOUNTED MONITORING SWITCH

William G. Roller, Purdy, Mo., assignor to
G & R Industries, Inc., Purdy, Mo.

Filed June 17, 1974, Ser. No. 479,863

Term of patent 14 years

Int. Cl. D13—03

U.S. Cl. D26—13 C

— I — . 1

— I — . 2

— I — . 3

FIG. 1 is a front view of the panel mounted monitoring switch of the present invention.

FIG. 2 is a top plan view of the panel mounted monitoring switch of FIG. 1.

FIG. 3 is a view of one side of the panel mounted monitoring switch of FIG. 1.

FIG. 4 is a rear view of the panel mounted monitoring switch of FIG. 1.

FIG. 5. is a bottom plan view of the panel mounted monitoring switch of FIG. 1.

FIG. 6 is a view of the other side of the panel mounted monitoring switch of FIG. 1.

I claim:

The ornamental design for a panel mounted monitoring switch, substantially as shown and described.
